CLAUDE R. SWAIM, OF MUNCIE, INDIANA, ASSIGNEE TO ORIN H. McDOWELL, OF STEUBENVILLE, OHIO.

DOOR-HOLDER DEVICE.

1,225,285.

Specification of Letters Patent. Patented May 8, 1917.

Application filed January 20, 1917. Serial No. 143,442.

To all whom it may concern:

Be it known that I, CLAUDE R. SWAIM, a citizen of the United States, residing at Muncie, in the county of Delaware and State 5 of Indiana, have invented certain new and useful Improvements in Door-Holder Devices, of which the following is a specification.

This invention relates to improvements in 10 door-holding devices. That is to say,—devices for holding or retaining the door against movement from a fixed location in its open position.

The object of this invention is to provide 15 a device capable of being easily applied to doors of business buildings or dwellings, and by the use of which the door may be easily fastened at any desired point or location in its swing from the closed to the en- 20 tirely open position, and whereby it may be easily released.

I am aware that devices having the same general purposes as above stated have heretofore been made. Accordingly, the more 25 specific purposes of this invention are to provide a device of this character which will be simple and economical of construction, durable, and not liable to get out of order or repair; and which may be easily installed. 30 My improved door holder device consists of the new construction, combination and arrangement of parts shown in the annexed drawings and described in this specification; and the invention is defined in the ap- 35 pended claim.

Important features of utility of my improved door holder are, that it occupies small space, that a minimum amount of work is required for its installation, and 40 that the device is entirely contained and concealed within the mortise therefor in the door structure. In the present illustration of my invention the same is shown installed at the lower portion of the frontal edge of 45 an ordinary wooden door of usual thickness.

Suitable characters of reference are applied to the several parts of the device in the different views of the drawings.

50 In Figure 1 which shows the lower part of the door, is seen the face plate portion of the case or frame in which is contained the retaining and releasing means for the plunger element.

55 Fig. 2 is a view taken in the direction in-

dicated by the arrow 2 in Fig. 1, the door holder device being shown in elevation, and the door structure being shown in section.

Fig. 3 is a vertical central sectional view 60 of Fig. 2.

Fig. 4 is a frontal view showing the position of the parts when the device has been operated.

Fig. 5 is a vertical central sectional view 65 of Fig. 4.

My invention comprises a frame case of compact form and structure having a vertical face plate and vertical parallel sides; between these sides is slidably disposed an angular detent lug having a threaded hole 70 in its bottom and to which detent lug is hingedly connected a lift handle that normally hangs vertically in a slot provided therefor in the face plate. A spring pressed pawl which normally retains the detent lug at raised position has a push head 75 operable at the face plate so that when pressed inwardly the detent head is released; a tubular guide member adapted to be inserted to secure position in the bottom 80 of the door, a plunger in said guide member having a stem adapted to be screwed into the said detent lug, and a spring between the upper end of the tubular member and the plunger, to normally depress the 85 said plunger. By my invention as above outlined, comparatively slight cutting away of the door body is necessitated, and by merely the variation of the length of the 90 plunger stem the device is rendered capable of being operated at any desired height 95 on the door.

In preparation for the installing of the invention, a mortise cavity A of the shape shown in Fig. 2 is chiseled in the door. From the bottom edge of the door is then bored a hole B of the suitable diameter shown, and from this hole is extended a bore 100 C of smaller diameter and which opens into the cavity A.

The case or frame in which the actuating parts of my device are retained is made of thin sheet metal, the walls 1 of which case are soldered or brazed to the face plate 2. The transverse plate 3 constitutes a guide-way for the lower end of the lift handle 4 and the side arms 5 constitute guides for the pawl 6. To these said operative parts further reference will presently be made. Disposed slidingly between the side plates 1 105

and 1 and having on its sides the studs 7^a which are adapted to have movement slidingly in the guideways 8, is a detent lug 7. This detent lug has a beveled nose 7^b at its rear side. On a transverse pin in its frontal portion is pivotally connected a lift handle 4 of the form shown in Fig. 3. This lift handle 4 has the curved underside 4^a and is slidingly disposed between the plates 1 and 10 1 and its lower edge 4^b has bearing against the transverse plate 3. At the upper end of the lift handle is provided a tooth 4^c whose function is to engage the recess 7^c of the detent lug 7 when the lift handle is swung 15 or pulled up to the dotted line position shown in Fig. 5.

Disposed vertically in the door structure is the plunger member comprising a head and stem and the detent lug 7 hereinbefore referred to. In the bore of a cylindrical sheet metal shell 10 that is seated firmly in the hole B, is the metal plunger head 11. The bottom of this plunger head consists of a toe 11^a made preferably of rubber or fiber. The upper part of this plunger member comprises a stem 12, its lower end being secured to the plunger head. This stem is passed through the top of the shell 10 and its threaded upper end is adapted to be 20 screwed into a threaded hole in the detent lug 7. The opening 7^d of the hole in the detent lug is so flared that when the stem 12 is inserted thereat its threading entrance into the hole is facilitated. A coil spring 25 13 between the plunger head and the underside of the top of the shell 10 urges the plunger normally to the downward position.

The pawl member comprises the parts as follows: The vertically arranged pawl 6 has the tooth 6^a and the beveled face 6^b. An arm 15 which projects forwardly from this pawl rests slidingly in a hole provided therefor in the cross bar 14. A push head 16 formed on the end of the arm 15 rests 30 45 slidingly in a suitable bore therefor in the face plate 2 of the case. A coil spring 17 between the push head 16 and the cross bar 4 acts to urge the pawl 6 to forward position the tooth 6^a coming into engagement underneath the nose of the detent lug 7. In the face plate 2 is provided a slot 20 of width to permit of the free movement therein of the lift handle 4. The purpose of the enlarged opening 20^a is to permit of the free 50 55 insertion of a person's finger to position underneath the lower end of the lift handle 4. The lower end of this lift handle has a depression 4^e which renders easy the engagement thereof by the finger.

60 From the foregoing description, the construction, combination and arrangement of the several parts may be clearly understood. The invention in readiness to install comprises the case and its connected parts, and 65 the shell 10, plunger 11 and its stem 12.

The cavity A, hole B and bore C having been prepared, the case is first set in position as shown in Fig. 1. By insertion of screws 22 through the face plate 2 the case is held securely at place. Then the shell 70 10 is disposed at place in the hole B and is retained by the engagement of the crimped rim 10^a closely engaging the edge of the hole B. The plunger stem 12 passed up through the top of shell 10 and through the bore C is screwed into the detent lug 7. The action of the coil spring 13 in urging the plunger head downwardly holds the detent lug at tight engagement with the tooth 6^a of the pawl 6. The installation is now 75 80 complete and the device is in readiness for operating. As will be observed, the parts constituting my invention take up small space and are simply constructed and arranged. The device being entirely contained inside the door structure there are 85 no projecting parts.

Until there may be a necessity to retain the door at fixed location in its open position, the several parts of my improved door holder occupy the relative positions as shown 90 in Figs. 1, 2 and 3, the plunger 11 being retained at retracted position by the engagement of the nose of the detent lug 7 with the tooth 6^a of the pawl 6. The door being 95 swung open to the location desired, a slight pressure by the finger against the push head 16 causes the tooth 6^a to be disengaged from the detent lug. The spring 13 being then unresisted, its instant action causes a downward movement of the plunger head 11 the toe 11^a thereof making contact with the floor surface. The relative positions then of the several parts are as shown in Figs. 4 and 5.

To retract the plunger from the lowered 100 position and thereby to release the door from its position held as described, the finger is applied at the opening 20^a and at engagement with the depression 4^e of the lift handle 4 and thence as the lift handle is 110 swung outwardly and upwardly to the dotted line position as shown in Fig. 5, to the rounded portion 4^a. With the lift handle at the horizontal position, the tooth 4^c rests in engagement with the recess 7^c so 115 that upward movement of the lift handle causes, in turn, an upward travel of the detent lug and its connected parts. By an upward pull or lift then exerted upon the lift handle, the face 7^b of the detent lug passes 120 the face 6^b of the pawl 16, and simultaneously with the snap return of the pawl to position shown in Fig. 3, the detent lug 7 will have again been engaged, and the plunger head 11 will have been returned to 125 the normally raised position. The user's hold on the lift handle being then released, the lift handle swings by its own weight, back to the normal vertical position as shown.

This invention besides having the advan-

ages of simplicity of construction and operation, and of being easy to install, has the further advantage of being contained entirely in the door structure. By reason of 5 its being similar in general external structure to allied lines of hardware for doors, such as lock and bolt devices, the correct method of preparing the mortise openings and of placing the parts in position and connecting same, is capable of being readily understood and practised by a mechanic of ordinary ability.

There is the further advantage of the ease of manipulation or use of same, it being 15 obvious to any person that to exert a pressure on the push head 16 will cause action of the device, and again, it being quite as apparent that to cause a return of the plunger to the raised position, there would be 20 the use of the lift handle.

In this specification I have shown the form of embodiment deemed preferable. I am aware that minor changes may be made in the form and construction of the details 25 of construction without departing from the nature or spirit of the invention as defined by the appended claim, or of sacrificing any of its advantages.

What I claim as my invention, and desire 30 to secure by Letters Patent, is:—
A door holder device, comprising a frame

adapted to be seated in a mortise provided therefor in the door, the face plate of said frame having a vertical slot, a detent lug disposed slidingly between the sides of said 35 frame and having a threaded hole in its bottom side, and there being transverse studs on said detent lug to move in vertical guide-ways in said frame, a tubular guide member adapted to be inserted to secure position 40 in the bottom of the door, a plunger slidingly disposed in said tubular guide member and having an upwardly disposed stem adapted to be screwed into the said detent lug, a spring in said guide member to normally depress the said plunger, a spring 45 pressed pawl retained slidingly between the sides of said frame to engage and hold the detent lug at the raised position but which pawl is adapted to be shifted from said en- 50 gaged position, and a lift handle loosely connected to the said detent lug and arranged to normally hang in the slot of said face plate but which when swung outwardly has fixed engagement with the detent lug. 55

In testimony whereof I affix my signature in the presence of two witnesses.

CLAUDE R. SWAIM.
